(57) **CLAIM**

The ornamental design for a wall mounted storage rack with underside canisters, as shown and described.

DESCRIPTION

FIG. 1 is a front elevation view of a wall mounted storage rack with underside canisters showing my new design;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof; and,

FIG. 7 is an isometric view thereof.
